MACHINE FOR LOADING CARTRIDGES.

1,282,610.

Specification of Letters Patent. Patented Oct. 22, 1918.

Original application filed February 3, 1917, Serial No. 146,391. Divided and this application filed June 6, 1917. Serial No. 173,080.

To all whom it may concern:

Be it known that I, WILLIAM I. MACOMBER, a citizen of the United States, residing at Cranston, in the county of Providence and State of Rhode Island, have invented certain new and useful Improvements in Machines for Loading Cartridges, of which the following is a specification.

My invention relates to machines for loading cartridges, and especially to the feeding and conveying mechanism thereof. The present application is a division of application Ser. No. 146,391 filed February 3, 1917.

The essential objects of my invention are to deliver the articles to be fed, such as shells or bullets, to their respective carriers automatically, and timed suitably to the movements of the carriers, and to automatically correct any false position of the articles before delivery to their carriers.

My invention consists in the features of construction, combinations of elements, and arrangement of parts which fall within the scope of the appended claims.

In the accompanying drawings which form a part of this specification, and in which is shown merely a preferred form of embodiment of my invention,

Figure 1 is a front elevation of a cartridge loading machine embodying my invention, omitting such parts of the machine as are remote from the subject of this invention.

Fig. 2, an end elevation of the same.

Figs. 3, 4, 5 and 6 sections of the same on lines 3—3, 4—4, 5—5, and 6—6 respectively of Fig. 1.

Figs. 7 and 8 a plan view and vertical central section respectively of the shell conveyor.

Fig. 9, a section on line 9—9 of Fig. 1.

Fig. 10, a detail elevation of the shell clasp taken at a different angle from that shown in Fig. 8.

Fig. 11, a transverse section of the same.

Figs. 12, 13, and 14, sections on lines 12—12, 13—13, and 14—14 respectively of Fig. 7.

Fig. 15, a section of a portion of the bullet carrier and feed on line 5 of Fig. 1.

Fig. 16, a section of a portion of the shell carrying disk on line 16 of Fig. 1.

Fig. 17, a section on line 17 of Fig. 1.

Figs. 18 and 19 detail views of the bullet and shell feeding cams respectively.

Figs. 20 and 21, a plan and vertical section respectively of the bullet conveyer or rectifier mechanism.

Fig. 22, a section on line 22 of Fig. 20.

Fig. 23, a plan on lines 23 of Fig. 22.

Figs. 24, 25, 26 and 27 sections respectively on lines 24, 25, 26, and 27 of Fig. 20.

Figs. 28, 29, 30 and 31, a front elevation, side elevation, transverse section, and rear elevation respectively of the bullet clasp, and

Fig. 32, a section on line 32 of Fig. 1.

Like reference characters indicate like parts throughout the views.

In the embodiment of my invention herein set forth the framework of a shell loading machine comprises a base 35, posts 36, table 37, end uprights 38, cross piece 39, and bearings 40 for the driving shaft 41. 42 and 43 are the bearings for the shafts 44 and 45 of the shell carriers 46 and 47 respectively, rotatable step by step. The carrier 46 is driven by a cam 49 on the shaft 41 engaging a cam roller 50 on lever 51 pivoted to spindle 44 supported by bridge 52. A pawl 53 on this lever engages the teeth 54 of a wheel 55 fast to the spindle 44. A spring 56 attached to the pawl and lever draws the pawl into engagement with the wheel. Similar movement is imparted to the bullet carrier disk 47 by cam 58 on the main shaft through cam roller 59 on lever 60, pivoted on spindle 45, and carrying pawl 61 engaging the teeth 62 of wheel 63 fast on spindle 45. The pawl is tensioned by spring 64.

Shells are fed thus to the shell carrier 46. Fast on the cross piece 39, as shown in Fig. 1, is a circular plate 66 with an opening 67 registering with an opening 68 in the cross piece. On this plate is a tubular post 69 embraced by the neck 70 of a conical hopper 71 containing a supply of empty shells. Slidable in the post is a reciprocating tube 72 extending below the cross piece and fast to a cross head 73 carrying a pin 74 movable in a vertical slot 75 in one of the uprights 38. A rod 76 connects this pin to a crank 77 on a shaft 78 mounted in bearings 79 in the uprights 38. This shaft is driven, as shown in Fig. 4, by a sprocket wheel 81 on the main shaft through chain 82 on sprocket 83 on a shaft 84 in a bearing 85 fast to the lower face of the table. A second sprocket 86 on the shaft 84 drives a chain 87 engaging a sprocket 88 on shaft 78, as shown in Fig. 6.

The described mechanism vertically reciprocates the tube 72 from below the top of the post 69 to a point in the hopper, thus coöperating with the inclined wall of the hopper to agitate the shells and induce them successively downward. Fast to the upright below the cross head is a support 90 rigidly holding a tubular guide 91 which telescopes the tube 72 and extends into the post forming a conductor section. The lower portion of the guide has a vertical slot 92 sufficiently broad to admit the passage therethrough of an upright shell. Embracing the guide is a clasp which, as shown in Figs. 8, 10, and 11, 10 consists of a vertically disposed fixed hinge member 94 fast to the guide having shoulders 95 carrying a spindle 96, upon whose ends are pivoted curved arms 97 and 98; arms 97 being fixed to a substantially cylindrical shell 99, and arms 98 being fixed to a similar shell 100. These hinged sections are pressed around the guide by means of a spring 102 upon the pintle with its ends pressing against the outer faces of the sections. The adjacent margins of the sections are cut away for some distance forming a vertical opening 103, at the upper end of which are laterally extending cavities 104. The sections yield to permit an empty shell 15 to be drawn out of the lower end of the guide, and the cavities 104 facilitate the delivery of a reversed shell.

To insure that each shell shall be delivered to the carrier 46 head downward 20 the following reversing mechanism, shown in Figs. 7 and 8, is employed. This comprises a circular conveyer 106 with radial openings 107 and a central opening or bearing 108. This member is rotatable with its periphery in slidable contact with a rim 109 25 fixed to a circular base 110 by screws 111. The member 106 rests upon the base supported upon a bracket 112 upon the upright 38. The conveyer member 106 is intermittently rotated thus. Frictionally engaged in the central opening 108 of the conveyer is a split ring 113 surrounding the upper end 114 of a shaft 115. This shaft rotates the member 106 under normal conditions, but, as will be later described, the member is intermittently locked, during 35 which period of inaction it is essential that the shaft 115 continue its rotation independently of said member. To this end the split ring 113 has at its adjacent ends tapering threaded holes 116 adapted to receive a threaded tapering wedge 117. By screwing the wedge up and down in the holes any degree of frictional engagement between the 40 member 106 and 113 is secured. The rotary ring is attached to the shaft 115 by either a removable spline or a screw 118. A washer 119 fixed to top of shaft 115 assists the retention of the conveyer. A gear 120 on the 45 shaft 115 meshes with a gear 121 fast on a

shaft 122 journaled in the uprights having a sprocket 123 driven by a chain 124 from a sprocket 125 on the main shaft. Thus continuous motion is imparted to the shaft 115. The means for intermittently locking the 50 conveyer 106 during this rotation to produce a step by step motion timed with the carrier 46 is as follows: The member 106 has an annular series of openings 126 adapted to register with a hole 127 in the base 110, as 55 shown in Fig. 9, in which is slidably mounted a vertical pin 128 adapted to intermittently project into one of the openings 126. The pin is normally held with the upper end in one of the openings by virtue 60 of a collar 129 near its upper end against which abuts a helical spring 130 resting on a resultant shoulder 131 in the opening 127. In the pin 128 is an opening 132 which loosely receives the end of an arm 133 upon 65 a plate 134 pivoted on a screw 135 fixed in a plate 136 upon the base 110. Upon one end of the plate 134 is a projection 137 engaging a projection 138 upon a lever plate 139 pivoted upon a screw 140 fixed in the outer 70 end of a lever 141 pivoted at 142 to the plate 136. To one end of plate 139 is fixed the end of a spring 143 attached at its opposite end to a pin 144 in the lever 141. The means for pulling the pin 128 out 75 of its seat in one of the holes is as follows: The outer end of the lever arm 141 is pivotally connected with the yoke portion 146 of a vertical rod 147 to whose lower end, as 80 shown in Fig. 3, is fixed a rod 148 fast to a head 149, vertically reciprocable on guide rods 150 through openings 151 in the head. The guide rods are rigid on a block 152 fixed to the table. The head, as shown in Fig. 17, is fast to the rod 153 which passes 85 through openings 154 and 155 in the base and table respectively. Upon the rod 153 is a plate 156 provided with a central opening 157 to loosely embrace the driving shaft 41. On the plate are cam rolls 158 and 159 90 engaging respectively cams 160 and 161 on the driving shaft. These cams reciprocate the head, and through the described lever connections, intermittently depress the pin 128 and unlock the conveyer 106 so that the latter has a step by step motion.

The empty shells are received in the conveyer through the tube 91 as follows when the head thereof is downwardly directed: The head enters one of the slots 107 of the member 106 at one end thereof and rests upon the face of the base 110. The rotary movement of the conveyer draws the shell out of the lower end of the tube 91 through the slot 92 this distending the plates 93 100 and 100 and permitting passage through slot 103. The empty shell is at this instant in vertical position and it is essential that it be laid down in a horizontal plane with its head adjacent the periphery of the conveyer. This is 105

accomplished by gravity in conjunction with an arcuate groove or angular recess 162 in the base 110, as shown in Figs. 7 and 8. The head of the shell rests upon the marginal portion 163 of the recess 162, and the weight 5 of the shell tilts and throws it upon its side into the radial slot 107 in which position the shell is carried in the direction of the arrow shown in Fig. 7 to a curved discharge 10 opening 164 in the base 110 at its periphery, where the weight of the head impels the shell head-first downwardly through a guide 165 whose upper end is fixed to the base, and whose lower end leads to a point adjacent 15 the shell carrier 46. When, however, the shell leaves the hopper with its open end downwardly directed, and it is therefore necessary to reverse its position before it reaches the shell carrying disk, the course of 20 the shell is as follows. It enters the radial slot 107 with its open end in contact with the marginal portion 163 of the base, and by gravity and the recess 162 is tilted and thrown upon its side with its open end to- 25 ward the periphery of the conveyer. It is essential that the shell be reversed before entering guide 165. This result is attained as follows: During the rotation of the conveyer the head of the shell falls by gravity 30 into the broad end 166 of an inclined tapering arcuate slot 167. This slot or groove extends from a point near the center of the base to a point 168 near the periphery thereof. The latter portion is the most narrow 35 and shallow; and adjacent this portion is a somewhat deeper portion or cavity 169. The described initial position of the shell is shown in broken lines in Fig. 12 with its open end somewhat elevated above the plane of 40 the upper face of the member 160. The shell in this position is carried into contact with the shoulder 170 upon a cam shaped plate 171 fixed to the wall 109 and extending in a horizontal plane over the top of the conveyer. From the shoulder 170 the cam plate 45 has a portion 172 corresponding with the curve of the channel 167. The shell, after its initial contact with the shoulder 170 is gradually elevated, as shown in Fig. 13, until it assumes a vertical position head down 50 which it maintains until the head reaches a narrow marginal surface 173 adjacent the auxiliary angular cavity 169 whereupon the head drops into the cavity by gravity and the shell falls upon its side with the head 55 toward the periphery of the conveyer. Thence the latter moves the shell along the upper surface of the base 110 until it reaches the opening 164 in the latter, and follows 60 the course of the shell already described.

The shell carrier disk 46, as shown in Fig. 16, has upper and lower peripheral flanges 174 and 175 provided respectively with semi-circular marginal cavities 176 and 177. The 65 shells are retained in these cavities by the

abutment 178 fixed to the table and contacting with the periphery of the flanges. There is a supporting surface 179 on the table below the shell carrier to support the heads of the shells.

70

The shells as they descend through the tube 165 are positioned vertically adjacent the carrier 46. The lower end of the tube, as shown in Fig. 16, is cut away to form a vertical opening 180. Through this opening the shell is automatically inserted into the carrier seats as follows: The tube is partially embraced by a wall 181 fast to the table and having an extended portion 182 provided with a bore 183 registering with an opening 184 in the wall of the tube 165. In the bore 183 is a plunger 185 carrying a pin 186 movable in a slot 187 in the wall. The plunger is normally held out of contact with the shell by a spring 188 which bears 85 against the wall and a shoulder 189 on the plunger. The plunger is intermittently moved against the successive shells as follows: Upon a post 190 is pivoted a lever 191 having in one end a slot 192 for the pin 186, and on the other end a cam roll 193 engaging the face 194 of a cam 195 on a depending arm 196 fixed to the head 149 and shown in Fig. 19. The movement of the head vibrates the lever to successively insert 90 a shell into its seat in the shell carrier at each advance of the latter.

The shell carrier advances the shell mechanism, not shown on the rear of the machine for inserting a powder charge. Thence 100 the charged shells are successively brought below and into vertical alignment with bullets carried by the bullet carrier 47, both carriers rotating step by step in the direction of the hands of a clock. The bullet 105 carrier comprises a peripheral flange 198 with radial openings 199 forming peripheral teeth 200 upon whose adjacent faces, as shown in Fig. 3, are pairs of resilient clips or fingers 201 adapted to form temporary 110 seats for bullets to be inserted into the shells by a die 202 in head 149 as shown in Fig. 17.

The bullets 203 are of oblong shape with a blunt base and a pointed or rounded top. It is necessary that the bullets be inserted 115 into the seats 201 base downward. The parts and mechanism for feeding these bullets are similar in most respects to those for feeding the shells.

The bullet hopper 204 embraces a hollow 120 post 205 carried by a plate 206 on the cross piece. The cross head 207 which carries the reciprocating tube 208 is moved through its pin 209 by connecting rod 211 and the crank 212 on shaft 78. The tubular guide 125 213 is rigidly carried by the support 214 on the upright, and has a delivery slot 215 in its lower end. The bullet delivery clasp, as shown in Figs. 24 to 31 inclusive, comprises the hinge shoulder 216, lugs 217, 130

4

pintle 218, the arms 219 and 220 carrying shells 221 and 222 respectively, and the spring 223. The shells are cut away to form a vertical opening 225. The bullet rectifying mechanism, as shown in Figs. 20 and 21, includes the conveyer member 226, having the slots 227 and opening 228, and resting on the base 229 within the rim 230. The base is supported by a bracket 231 on one 10 of the uprights 38. The bullet conveyer actuating mechanism comprises the split ring 233 around shaft 234 expanded by the wedge 235 and attached to the shaft by screw 236. The gear 237 on shaft 234 15 meshes with gear 238 on shaft 122. The locking openings 239 in the conveyer 226 register with the hole 240 in the base in which is the pin 241 pressed by spring 243 and engaged by the arm 244 on the plate 245 20 pivoted at 246 to the base plate 247. A projection 248 on the plate engages a projection 249 on a yielding plate 250 pivoted at 251 to a lever 252 pivoted at 253 to the base plate. This lever is connected to the yoke 254 portion 254 of the rod 147. The step by 25 step motion of the conveyer 226 is thus timed with the conveyer 106. A bullet descending through tube 213 base downwardly enters a slot in the conveyer whereby the 30 bullet is drawn through the slot 225 and falls into a horizontal position in the slot with its point directed toward the axis of the conveyer by means of the angular recess 256 in the base 229 as shown in Fig. 21. In 35 this position the bullet is carried in the direction of the arrow shown in Fig. 20 to an inclined discharge opening 257 in the base; whence it drops base downwardly through a conductor 258 extending downwardly from the base. If, however, the bullet 40 leaves the hopper point downward, gravity coöperating with the cavity 256 throws the bullet on its side with its point outward as shown in Fig. 20. The bullet 45 is reversed by being moved over the end 260 of an arcuate slot 261, which end is of greater depth than elsewhere, but which gradually shallows and decreases in width as it approaches its opposite end adjacent 50 the periphery of the member 226. At the shallow end of the channel is a deeper cavity 262. When the base of the bullet falls into the cavity 260 the bullet is inclined as shown in Fig. 24; and as it progresses along the channel 261 as shown in 55 Fig. 25 the bullet assumes a vertical position until it reaches the cavity 262 where the bullet is tilted to a horizontal position with its point directed to the axis of the 60 conveyer and positioned to fall through the conductor 258.

The lower end of the conductor 258, as shown in Fig. 15, has a lateral opening 264 enlarged by a cavity 265 to admit the clips 65 201. The bullet injecting device is like the

described shell injector comprising the housing 267 on the table and carrying the plunger 269 pressed by a spring 270. A pin 271 in the plunger is loose in a slot 272 in a lever 273 pivoted to a post 274 on the table and carrying a roll 275 engaging the face 276 of a cam 277 fixed to the head 149 as shown in Figs. 3 and 18. The plunger at each reciprocation inserts a bullet from the conductor into a pair of clips 75 75 as the carrier advances a step. Thus both the shells and bullets are automatically rectified fed and brought into successive registration with each other by gravity and operative connections actuated primarily 80 from the shaft 41 driven from its pulley 279.

I claim,

1. In a loading machine, the combination of a frame, a carrier upon the frame, a conveyer base on the frame above the carrier, a rim on the base, a rotary conveyer provided with radial slots embraced by the rim, a vertical guide on the frame with its end adjacent the conveyer and provided with a slot in its end, a clasp embracing the slotted portion of 90 the guide, a guide extending from the base to the carrier, and means for rotating the conveyer.

2. In a loading machine, the combination of a conveyer base provided with a hole, a rotary shaft journaled in the base, a conveyer provided with radial slots on the base frictionally engaging the shaft and provided with a series of openings adapted to register with the hole, a reciprocating locking pin 95 100 slidably mounted in the hole openings, and means rotating the shaft for reciprocating the locking pin.

3. In a loading machine, the combination of a conveyer base, a shaft rotatably mounted 105 in the base, a conveyer on the base yieldingly engaging the shaft, means for continuously rotating the shaft, and means for intermittently locking the conveyer during the rotation of the shaft.

4. In a loading machine, the combination with two guides, of a conveyer base between the guides provided with a curved groove in its top face, and with an angular cavity at one end of the groove, and with an angular 115 recess adjacent the other end of the groove, a rotary conveyer provided with radial slots on the base, a rim on the base surrounding the conveyer, a cam plate on the rim extending over the conveyer, and means for rotating the conveyer.

5. In a loading machine, the combination with an upper and lower guide, of a conveyer base between the guide provided with an inclined tapering groove in its top face and with an angular cavity at one end of the groove, and with an angular recess adjacent the other end of the groove, a rotary conveyer provided with radial slots on the base, a rim on the base, a cam plate on the rim 125 130

extending over the conveyer, and means for rotating the conveyer.

6. In a loading machine, the combination with a feed guide and delivery guide, of a conveyer base between the guide provided in its top with a groove and with cavities at the ends of the groove, and with an angular recess in alinement with the feed guide and adjacent one of the cavities, a rotary conveyer provided with radial slots on the base, and means for rotating the conveyer.

7. In a loading machine, the combination of a horizontally disposed rotary carrier provided with peripheral seats for articles, a hopper above the carrier, guides extending from the hopper to a point beside the carrier, means in the guides for reversing the articles, a reciprocating plunger in the guides in

the plane of the carrier movable toward and from the carrier, and means actuating the carrier for operating the plunger.

8. In a loading machine, the combination of a horizontally disposed rotary carrier provided with peripheral seats for articles, a hopper above the carrier, a rotary reversing conveyer between the hopper and carrier, a guide connecting the hopper and conveyer, a guide extending from the conveyer, to a point beside the carrier seats, a reciprocating plunger in the second guide for injecting articles into the seats, and means actuating the carrier for operating the conveyer and the plunger.

In testimony whereof I have affixed my signature.

WILLIAM I. MACOMBER.
